CLAIM

The ornamental design for a cleaning cart, as shown and described.

DESCRIPTION

FIG. 1 is an isometric view of a cleaning cart according to the present disclosure;

FIG. 2 is a first side view of the cleaning cart of FIG. 1;

FIG. 3 is a second, opposite side view of the cleaning cart of FIG. 1;

FIG. 4 is a front view of the cleaning cart of FIG. 1;

FIG. 5 is a back view of the cleaning cart of FIG. 1;

FIG. 6 is a top view of the cleaning cart of FIG. 1; and,

FIG. 7 is a bottom view of the cleaning cart of FIG. 1.

The broken lines shown in the figures are included for the purpose of illustrating portions of the cleaning cart and form no part of the claimed design.
